ATTORNEY.

UNITED STATES PATENT OFFICE

ORVILLE MITCHELL, OF DALLAS, TEXAS

COTTON FEEDING, SEPARATING, AND CLEANING MACHINE

Application filed May 10, 1930. Serial No. 451,290.

This invention has for its general object to improve cotton feeding separating and cleaning machines of the type employing multiple separating units and as illustrated, for example, in Patent No. 1,734,592, granted to John E. Mitchell, November 5, 1929.

In the type of machine referred to, each saw cylinder of a separating unit has an associated hull board for directing the mixed 10 cotton, hulls and trash against the surface of its saw cylinder, and the lower end of which, as usual, defines the size of an opening past the saw cylinder for the escape of hulls and trash. The impossibility of adjusting the size of this opening to secure 15 ideal results has always been recognized. That is to say, if the opening is made small enough to prevent the escape of cotton past the saw cylinder, the free discharge of hulls 20 will be retarded, and the machine will ultimately choke up. On the other hand, if said opening is made large enough to permit the free discharge of hulls and trash, it inevitably results that a fairly large proportion of 25 cotton will escape with the hulls and trash.

It is a comparatively easy matter to recover the cotton escaping past the first saw cylinder of a multiple cylinder machine, as, for example, by positioning a reclaiming 30 saw cylinder and cooperating brushes below the passage between the lower end of the hull board and the saw cylinder, and which operates to engage and return the escaping cotton to the saw cylinder. Such 35 an arrangement, in connection with a single saw cylinder machine, is shown in said Mitchell's prior Patent No. 1,613,242, dated January 4, 1927.

In the case of the saw cylinder of the 40 second separating unit, or of succeeding separating units if more than two are employed, the case is otherwise, as it has not been heretofore deemed feasible to recover the escaping cotton, owing to the multiplicity of mechanism that would be required, the added expense that would be involved 45 and the difficulty of constructing such a machine within the limit of size permitting it to be installed on an ordinary gin stand.

As a matter of fact, in the machine of Pat-

ent No. 1,734,592 referred to, no attempt is made to recover the cotton escaping past any of the saw cylinders.

In this type of machine the waste of cotton is prevented, as far as possible, by gradually reducing the size of the hull discharge opening in each succeeding separating unit.

According to the present invention, I dispense with the use of a hull board in connection with the second saw cylinder of the two cotton separating units employed, and provide for the free discharge of mixed cotton, hulls and trash from the second separating unit and its return past the saw cylinder of the first separating unit and finally 60 to a reclaiming saw cylinder cooperating with said latter saw cylinder.

A reclaiming saw cylinder in cooperation with brushes, as described in Patent No. 1,613,242 referred to, enables a very close 70 separation between cotton and hulls to be made, because the hulls are continuously discharged directly from the machine and the cotton is continuously removed from the reclaiming saw cylinder by the saw cylinder 75 with which it cooperates.

By the above arrangement I provide a continuous path of treatment for the cotton and utilize both sides of the main saw cylinder, or that of the first separating unit, 80 in separating cotton from the mixed cotton, hulls and trash fed into the machine.

Furthermore by dispensing with a hull board for the second saw cylinder and so arranging the path of movement of the cotton through the machine that the main saw cylinder and its cooperating reclaiming saw cylinder function simultaneously to remove cotton from the main bulk of mixed cotton, hulls and trash fed into the machine and 90 from mixed cotton, hulls and trash freely escaping past the saw cylinder of the second separating unit, I am enabled to produce a machine very compact in structure, and relatively small in size as compared 95 with machines of the multiple type as heretofore designed, and the saving in space thus effected makes it possible to combine in the machine a cleaning unit which receives, cleans, and delivers from the ma- 100

chine the cotton removed by the saw cylinder of the second separating unit. The added cleaning mechanism constitutes the subject matter of a separate application 5 Ser. No. 451,273, filed May 10, 1930, and is the invention of the said John E. Mitchell. It is sufficient to say at this point that it involves a doffer common to the final cotton separating unit and the cotton 10 cleaning mechanism, and which operates to remove the cotton from the saw cylinder of said separating unit, deliver it to the cleaning mechanism, and then to receive the cleaned cotton from the latter mechanism and discharge the same from the machine.

It should be stated further, that by increasing the effective operating surface of the saw cylinder of the first separating unit, 20 by causing it to act at opposite sides, respectively, on two streams of mixed cotton, hulls and trash, I can use a much smaller saw cylinder in the second separating unit, and this fact, combined with the absence of 25 a hull board and the arrangement for a continuous path of treatment of the cotton as above described, makes it possible to provide a combined cotton feeding, separating and cleaning machine of the multiple type of such relatively small size that it may be installed on an ordinary gin stand.

The preferred embodiment of the invention is characterized by a main saw cylinder 35 having a hull board associated therewith; a reclaiming saw cylinder mounted below the opening between the lower end of said hull board and said main saw cylinder and in working relation to the surface of the latter; a kicker roller and a doffing cylinder co-operating with the main saw cylinder; a second saw cylinder, having a kicker roller and a doffing cylinder co-operating therewith, positioned to receive the product removed from the main saw cylinder and located at a distance from the latter to provide a free, open space for the discharge of mixed cotton, hulls and trash between the two saw cylinders; means for directing 40 the mixed cotton, hulls and trash so discharged past the main saw cylinder and in engageable proximity to the surface thereof; and, finally, by means for directing the remaining product on to the reclaiming saw cylinder, and providing for the escape of 45 hulls and trash past the same.

The invention is illustrated in the accompanying drawing, in which the figure is a longitudinal sectional view of a machine constructed according to my invention, and showing a cotton cleaning unit combined therewith.

Referring now to the drawing, the numeral 1 indicates the casing of the machine, 60 in the side walls of which are suitably

journalized the shafts of the various rotating members hereinafter described. As the manner of mounting such rotatable members is well known, and as the driving mechanism for rotating the same is of conventional type, I have simply shown in section the shafts of the various rotating members and indicated by arrows the directions of their rotation.

The casing 1 is provided with a feed opening 2 in its upper end, and mounted below this opening are feed rollers 3. Below the latter is a breaker cylinder 4 which rotates in proximity to a screen 5 mounted in the rear of the casing. Located below the screen 50 5 is a hull board 6, the lower end of which defines the size of an opening 7 past a main saw cylinder 8. Mounted below the saw cylinder 8, and in working relation with the surface thereof, is a small reclaiming saw 85 cylinder 9. At its lower end the hull board 6 is bent outwardly at right angles to itself, as indicated at 10, and then is bent again inwardly at right angles to provide a wall 11, in the lower end of which is mounted a bar 90 12 containing a row of brushes 13. The wall 11 and brushes 13 serve to confine the product passing through the opening 7 and to direct it on to the surface of the reclaiming saw cylinder 9. A second row of brushes 14 95 is suitably mounted, as indicated at 15, on the opposite side of the reclaiming saw cylinder to that of brushes 13. The reclaiming saw cylinder 9 and its brushes function, in connection with saw cylinder 8, in a manner fully described in the patent to Mitchell No. 1,613,242 above referred to, and as will be briefly indicated hereinafter. The main saw cylinder 8 is of relatively large size and has cooperating therewith a kicker roller 16 100 and a doffing cylinder 17. The main saw cylinder 8 and the parts associated therewith constitute the first of two separating units employed in carrying out the purposes of this invention. The second separating 105 unit comprises a saw cylinder 18, which may be of much smaller diameter than the main saw cylinder 8, and has cooperating therewith a kicker roller 19 and a doffing cylinder 20. The saw cylinder 18 is so positioned 110 that the product removed from the main saw cylinder 8 by the doffing cylinder 17 will be thrown by the latter directly onto its surface. It is further positioned at such distance from the main saw cylinder 8 as to provide a free, open space 21 through which 115 hulls and trash knocked back by the kicker roller 19, and small locks of cotton not engaged by the teeth of saw cylinder 18, may be freely discharged, either by the action of gravity, or impact therewith of the blades of the kicker roller. Extending from a point close to the surface of saw cylinder 18 to a point beneath the main saw cylinder 8 120 is an inclined deflecting board 22 which, at

130

its lower end, is preferably continued in a horizontal direction, as indicated at 23, and from the end of this horizontal portion it is downwardly inclined to provide a hull board 24 for the reclaiming saw cylinder 9, and the lower end of which hull board defines the size of an opening 25 past the reclaiming saw cylinder.

The cleaning mechanism includes a cleaning cylinder 26 mounted to rotate in proximity to a screen 27 which partly surrounds it on its under side. The parts are so positioned that cotton is removed from the saw cylinder 18 by the doffing cylinder 20, which 10 15 20 25 30 35 delivers same to the cleaning cylinder 26 from its upper side, and then receives the cleaned cotton from the machine through an outlet 28. The trash passing through screen 27 falls in to a conveyor 29, whence it is discharged from the machine. The operation is as follows:

The raw product, consisting of mixed cotton, hulls and trash fed into the machine by feed rollers 3 is acted upon by the breaker cylinder 4 and carried thereby over the screen 5, through which some of the trash falls. The product passes thence on to the hull board 6 down which it is propelled by the breaker cylinder into engagement with 20 25 30 35 the surface of the main saw cylinder 8. The main body of cotton will be engaged by the teeth of this saw cylinder and carried under kicker roller 16 which will knock back part of the hulls and trash mixed with the cotton. The doffing cylinder 17 removes from saw cylinder 8 the cotton carried beneath kicker roller 16 and discharges it on to the surface of the second saw cylinder 18.

The hulls and trash knocked back by 40 45 50 55 kicker roller 16, and small locks of cotton not engaged by the teeth of saw cylinder 8, fall through the opening 7 provided by hull board 6 and on to the surface of reclaiming saw cylinder 9. As this saw cylinder passes under the brushes 13, the latter offer a sufficient resistance to cause the teeth of the saws to engage the small lock cotton while the hulls and trash are readily and rapidly thrown off. In passing over 50 55 60 65 70 75 80 85 90 95 100 105 110 115 120 125 130 brushes 14 the locks of cotton are caused to be engaged still more strongly by the teeth of the saw cylinder, and prevented from being thrown off from the surface of the saw cylinder by centrifugal action. Cotton is removed from the reclaiming saw cylinder by the main saw cylinder 8, which has a surface speed of rotation greater than that of the reclaiming saw cylinder.

The kicker roller 19 will knock back hulls 60 65 70 75 80 85 90 95 100 105 110 115 120 125 130 and trash from the cotton carried under it by saw cylinder 18 and such hulls and trash, together with small lock cotton not engaged by saw cylinder 18, will be discharged freely through opening 21 and fall on to the deflecting board 22. The latter causes this

mixed product to be carried past the saw cylinder in engageable proximity thereto, and especially at the horizontal portion 23 of the deflecting board, so that the teeth of saw cylinder 8 will engage and remove a 70 75 80 85 90 95 100 large portion of the locks of cotton in this product. The remainder of the product then passes over hull board 24 and the reclaiming saw cylinder 9 engages and removes practically all of the remaining 75 80 85 90 95 100 cotton and carries it under the saw cylinder 8, by which it is removed. The hulls and trash now almost entirely free of cotton particles, discharges through the opening 25, falls on to an inclined slide board 30, and is discharged out of the machine.

From the above operation it will be seen that both the main saw cylinder 8 and the reclaiming saw cylinder 9 are caused to do double duty, both reclaiming cotton from 85 90 95 100 the raw product fed into the machine at one side of the saw cylinder, and from the product discharged from the second cleaning unit and caused by the deflecting board 22 and hull board 24 to pass into engagement with the main saw cylinder at the sides of the latter opposite that operating upon the raw product. It will also be seen that as to part of the raw product, I provide a continuous path of treatment beginning at one side of the reclaiming saw cylinder, continuing over the main saw cylinder and returning past the latter to the other side of the reclaiming saw cylinder.

I wish it understood that the invention is not to be limited to the exact construction and arrangement of parts shown and described, except as may be required by certain of the claims following.

I claim:

1. In a cotton feeding, separating and cleaning machine, in combination with feeding means, a cotton separating unit including a main saw cylinder, a second cotton separating unit comprising a saw cylinder positioned to receive the product from the first separating unit, the two units being so positioned as to afford a space between them for the free discharge of mixed cotton, hulls and trash rejected by the second cotton separating unit, means for directing the product fed into the machine and said discharged product, respectively, in two different streams along opposite sides of said main saw cylinder and toward a common point, and a reclaiming saw cylinder located at such point in working proximity to the main saw cylinder and in the path of movement of each stream, and operating to engage and remove cotton simultaneously from both streams and return the same to the main saw cylinder.

2. In a cotton feeding, separating and cleaning machine, a cotton separating unit

- comprising a main saw cylinder, means for feeding the raw product thereto, hull rejecting and cotton removing means cooperating with said saw cylinder, a second cotton separating unit comprising a saw cylinder having hull rejecting and cotton removing means cooperating therewith and positioned to receive the product removed from the main saw cylinder, and at such distance 5 from the latter as to permit the free discharge between the two cylinders of mixed cotton, hulls, and trash escaping from said second separating unit, means for directing the raw product and the product discharged 10 between the two saw cylinders, respectively, in two different streams past opposite sides of the main saw cylinder and toward a common point, and a reclaiming saw cylinder located at the point of convergence of said 15 streams in working relation to said main saw cylinder and adapted to engage cotton in each stream and return it to the main saw cylinder.
3. In a cotton feeding, separating and 20 cleaning machine, in combination with a main saw cylinder, means for feeding the raw product thereto, a second saw cylinder, hull rejecting and cotton removing means cooperating with each of said saw cylinders, 25 said second saw cylinder being positioned to receive the product removed from the main saw cylinder and being separated from the latter a sufficient distance to permit the free escape of cotton and hulls between the 30 two, a reclaiming saw cylinder positioned to receive and return to the main saw cylinder cotton escaping past the same, and means for directing the mixed cotton, hulls and trash falling between the two saw cylinders to 35 said reclaiming saw cylinder, so that the cotton therein may be engaged by the latter and delivered to said main saw cylinder.
4. In a cotton feeding, separating and 40 cleaning machine, in combination with a main saw cylinder, means for feeding the raw product thereto, a second saw cylinder, hull rejecting and cotton removing means cooperating with each of said saw cylinders, 45 said second saw cylinder being positioned to receive the product removed from the main saw cylinder and being separated from the latter a sufficient distance to permit the free escape of cotton and hulls between the two, a reclaiming saw cylinder positioned 50 to receive and return to the main saw cylinder cotton escaping past the same, and means for directing the mixed cotton, hulls and trash falling between the two saw cylinders past, and in engageable proximity to 55 said main saw cylinder and then to said reclaiming saw cylinder.
5. In a cotton feeding, separating and 60 cleaning machine, in combination with a main saw cylinder, means for feeding the raw product thereto at one side thereof, a reclaiming saw cylinder positioned to receive and return to said main saw cylinder cotton escaping past the same, and cotton separating mechanism, including said main saw cylinder, positioned to afford a continuous path of treatment for the cotton from the reclaiming saw cylinder at one side thereof back to said reclaiming saw cylinder at the other side thereof, comprising hull rejecting and cotton removing means cooperating with said main saw cylinder, a second saw cylinder positioned at a distance from the main saw cylinder to permit the fall of mixed cotton, hulls and trash between the two, and adapted to receive the partially cleaned cotton removed from the main saw cylinder, hull rejecting and cotton removing means cooperating with said second saw cylinder, and means for directing the mixed cotton, hulls and trash falling through the space between the two saw cylinders past the main saw cylinder, on the opposite side thereof to which the raw product was fed, to the reclaiming saw cylinder. 70
6. In a cotton feeding, separating and 75 cleaning machine, in combination with a main saw cylinder, means for feeding the raw product thereto at one side thereof, a reclaiming saw cylinder positioned to receive and return to said main saw cylinder cotton escaping past the same, and cotton separating mechanism, including said main saw cylinder, positioned to afford a continuous path of treatment for the cotton from the reclaiming saw cylinder at one side thereof back to said reclaiming saw cylinder at the other side thereof, comprising hull rejecting and cotton removing means cooperating with said main saw cylinder, a second saw cylinder positioned at a distance from the main saw cylinder to permit the fall of mixed cotton, hulls and trash between the two, and adapted to receive the partially cleaned cotton removed from the main saw cylinder, hull rejecting and cotton removing means cooperating with said second saw cylinder, and means for directing the mixed cotton, hulls and trash falling through the space between the two saw cylinders past the main saw cylinder, on the opposite side thereof to which the raw product was fed, to the reclaiming saw cylinder. 80
7. In a cotton feeding, separating and 85 cleaning machine, in combination with a main saw cylinder and means for feeding the raw product thereto at one side thereof, a hull board, the lower end of which defines the size of a passage past such side of the saw cylinder for the escape of hulls, trash and small lock cotton, a reclaiming saw cylinder mounted in working proximity to the main saw cylinder below said passage, a kicker roller and a doffing cylinder cooperating with said main saw cylinder, a second 90
8. In a cotton feeding, separating and 95 cleaning machine, in combination with a main saw cylinder and means for feeding the raw product thereto at one side thereof, a hull board, the lower end of which defines the size of a passage past such side of the saw cylinder for the escape of hulls, trash and small lock cotton, a reclaiming saw cylinder mounted in working proximity to the main saw cylinder below said passage, a kicker roller and a doffing cylinder cooperating with said main saw cylinder, a second 100
9. In a cotton feeding, separating and 105 cleaning machine, in combination with a main saw cylinder and means for feeding the raw product thereto at one side thereof, a hull board, the lower end of which defines the size of a passage past such side of the saw cylinder for the escape of hulls, trash and small lock cotton, a reclaiming saw cylinder mounted in working proximity to the main saw cylinder below said passage, a kicker roller and a doffing cylinder cooperating with said main saw cylinder, a second 110
10. In a cotton feeding, separating and 115 cleaning machine, in combination with a main saw cylinder and means for feeding the raw product thereto at one side thereof, a hull board, the lower end of which defines the size of a passage past such side of the saw cylinder for the escape of hulls, trash and small lock cotton, a reclaiming saw cylinder mounted in working proximity to the main saw cylinder below said passage, a kicker roller and a doffing cylinder cooperating with said main saw cylinder, a second 120
11. In a cotton feeding, separating and 125 cleaning machine, in combination with a main saw cylinder and means for feeding the raw product thereto at one side thereof, a hull board, the lower end of which defines the size of a passage past such side of the saw cylinder for the escape of hulls, trash and small lock cotton, a reclaiming saw cylinder mounted in working proximity to the main saw cylinder below said passage, a kicker roller and a doffing cylinder cooperating with said main saw cylinder, a second 130

5 saw cylinder positioned to receive direct from said doffing cylinder the product removed from the main saw cylinder and located at a distance from the opposite side of the latter to provide a space between the two cylinders for the free passage between them of mixed cotton, hulls and trash falling past said second cylinder, and a deflecting board for directing such mixed cotton, hulls and trash past the main saw cylinder,

10 and terminating in a hull board associated with said reclaiming saw cylinder, and the lower end of which defines the size of an opening past said reclaiming saw cylinder for the escape of hulls and trash.

15 8. In a cotton feeding, separating and cleaning machine, in combination with a main saw cylinder and means for feeding the raw product thereto at one side thereof, a hull board associated with the saw cylinder at such side, a reclaiming saw cylinder located below the opening past the saw cylinder provided by said hull board and in working proximity to said saw cylinder, hull rejecting and cotton removing means 20 cooperating with the main saw cylinder, a second saw cylinder positioned to receive the product removed from the main saw cylinder and located at a distance from the opposite side of the latter to provide a space 25 between the two saw cylinders for the free discharge of mixed cotton, hulls and trash past said second saw cylinder, a deflecting board for directing such discharged product 30 past the main saw cylinder and having a portion positioned in close proximity to the surface of the main saw cylinder, and a hull board inclined downwardly from said latter portion of the deflecting board and the 35 lower end of which defines the size of an opening past the reclaiming saw cylinder for the escape of hulls and trash.

40 9. In a cotton feeding, separating and cleaning machine, two separating units, each 45 of which includes a saw cylinder having hull rejecting and cotton removing means cooperating therewith, the saw cylinder of the second unit being positioned to receive the cotton removed from the saw cylinder of the first unit, and each unit providing for 50 the discharge of mixed cotton, hulls and trash past its saw cylinder, and means common to the discharge of both units and operating to remove cotton from the discharged 55 product thereof and return same to the saw cylinder of the first unit.

60 10. In a cotton feeding, separating and cleaning machine, two separating units, each of which includes a saw cylinder having hull rejecting and cotton removing means 65 cooperating therewith, the saw cylinder of the second unit being positioned to receive the cotton removed from the saw cylinder of the first unit, and each unit providing for 70 the discharge of mixed cotton, hulls and

trash past its saw cylinder, and cotton reclaiming means including a saw cylinder mounted in working relation to the saw cylinder of the first unit and common to the discharge of both units and operating to remove cotton from the discharged product thereof and return same to the saw cylinder of the first unit.

75 In testimony whereof, I have hereunto set my hand.
